UNITED STATES PATENT OFFICE.

ALDEN L. McMURTRY, OF SOUND BEACH, CONNECTICUT, ASSIGNOR TO LOVELL-McCONNELL MANUFACTURING COMPANY, OF NEWARK, NEW JERSEY, A CORPORATION OF DELAWARE.

DIAPHRAGM-HORN.

1,299,201.

Specification of Letters Patent.

Patented Apr. 1, 1919.

Original application filed February 6, 1912, Serial No. 675,800. Divided and this application filed July 22, 1915. Serial No. 41,239.

To all whom it may concern:

Be it known that I, ALDEN L. McMURTRY, a citizen of the United States, and resident of Sound Beach, in the county of Fairfield and State of Connecticut, have invented certain new and useful Improvements in Diaphragm-Horns, of which the following is a specification.

This invention relates to a type of horn or warning signal most commonly used on automobiles, motor-boats and the like, wherein a vibratory diaphragm is used to produce the sound desired.

My present application is a division of my prior and co-pending application, Serial No. 675,800, filed February 6th, 1912. In said application I have disclosed several different improvements for transmitting the power from a source of power to the diaphragm so as to obtain effective vibratory movements of the latter with minimum injurious effect on the diaphragm. One of the forms disclosed in said application, and which is made the subject matter of the present application, relates to improvements for transmitting power from an outside source of power, such, for instance, as the engine of an automobile or motorboat, which is too powerful to be governed or have its speed limited by the action of the diaphragm.

The invention, one form of which is hereinafter described in detail, permits the manual connecting at will of the source of power and the rotary diaphragm-vibrating member, but at the same time automatically limits the speed of the latter, in case it tends to reach such a speed as might injuriously affect the diaphragm. Thus the horn may be properly sounded at will and without danger of injury to the horn, irrespective of the speed of the source of power.

In its preferred embodiment I incorporate two separate clutch devices within the horn casing where they are protected from dust and rain, and make them a part of the horn itself so that the connection to the source of power may be very readily made when the horn is attached to the vehicle or the support.

In the accompanying drawings, I have illustrated one embodiment of my invention. I do not desire to be limited to the specific construction illustrated in said drawings as it is

obvious that various changes may be made within the spirit of my invention and without departing from the scope thereof, as defined in the appended claims. Furthermore, I do not desire to be in any way limited to the specific mechanism for imparting vibrations to the diaphragm as such constitutes no part of my present invention. In these drawings, in which similar reference characters indicate corresponding parts in the figures:

Figure 1 is a side elevation of the operating mechanism within the casing, said casing being shown in section;

Fig. 2 is a transverse section on the line 2—2 of Fig. 1.

Fig. 3 is an end view of the friction clutch showing the drive shaft in section.

The specific form illustrated includes a cup-shaped casing 10 having a peripheral wall and a back wall 11, preferably integral therewith. At its front open end the casing 75 is secured to a plate 12, which latter is connected to a diaphragm casing 13. As shown, the plate and diaphragm casing are connected by screws 14. From a centrally located opening in the casing 13 extends a projector, or resonator, 15 of any desired or convenient form. Within the casing 13 is mounted a circular diaphragm 16, preferably of metal, held at its edges in any suitable manner, as for instance, between an annular shoulder on the interior of the casing and a retaining ring 17 and secured in position by screws 18.

Passing through the center of the diaphragm 16, and having one end rigidly secured thereto, is a spindle 19 which extends rearwardly through an opening in the plate 12 and through a spring 20 within the casing 10. The spindle is threaded and provided with nuts 21 adapted to be positioned 90 on the spindle so as to bear against the opposite sides of the spring and hold the latter at any desired point along the length of the spindle. One end of the spring is secured to the plate 12 adjacent to the periphery of the latter by means of an adjustable block 22 which need not here be described in detail except that it permits the spring to extend from the block, either parallel to the plate 12 or at a desired small angle in respect thereto.

Mounted on the plate 12 is a bracket 25 serving as a support for a rotatable shaft which latter carries a bevel gear 28, the size of which may be proportioned to the normal speed of the source of power. This bevel gear engages with a small bevel gear 31 at one end of a shaft 30 rotatable in supports 29. The shaft 30 at its opposite end has a bevel gear 32 meshing with a bevel gear 33 on a shaft 34 which is rotatable in supports 35. On the shaft 34, preferably at the center thereof, is mounted a toothed pinion 36, the teeth of which are adapted to contact with the free end of the spring 20, which end, as shown, is preferably curved and of narrowed width to permit of more compact and efficient construction.

From the foregoing description, it will be seen that the rotating of the gear 28 at a moderate rate of speed operates to cause a rapid rotation of the toothed pinion 36 by reason of the train of multiplying gears. The pinion 36, in rotating, contacts with the spring 20, and through it and the spindle 19, effects a vibratory movement of the diaphragm 16 to produce the desired sound.

The parts so far described form no portion of my present invention, and other means may be employed for effecting the vibration of the diaphragm upon the rotation of the member 28. For instance, the latter might be so positioned and its teeth so formed as to directly engage with the end of the spindle 19, or with any form of wear-piece carried by, or connected to, the diaphragm. A multiplying train of gears is not necessary and is desirable only in case normal speed of rotation of the member 28 is not sufficient to vibrate the diaphragm at the desired speed and to produce the desired sound.

The mechanism which embodies my present invention includes a support 40 secured within the casing 10, and having a bearing 45 for a shaft, preferably in alinement with a shaft carried by a bearing 25. This shaft which is carried by the bearing 40 has, at one end, a clutch member 41 with a plurality of clutch teeth thereon, and at the other end 50 has a cylindrical member 42. Adjacent to the gear 28 and carried by the same shaft as said gear is a member 43 provided with two projecting lugs to which are journaled arms 44. These arms are each formed with 55 an enlarged end portion and the opposite faces are so positioned and are so curved that they are adapted to rest upon the surface of the cylindrical member 42. The arms are drawn together and their curved 60 end surfaces pressed against the member 42 by means of a spring 45, the tension of which may be adjusted as desired by means of the screw and nut 46. From outside of the casing extends a drive shaft 47, illustrated as being flexible, and which leads

from any suitable source of power, such for instance as the fly-wheel or the engine of an automobile. The terminal portion 48 of this shaft, which is disposed within the casing, has a collar 49 feathered thereon and integral, or rigid with, the second half of the toothed clutch. Various means may be provided for shifting the collar 49. As shown, it has an annular groove receiving the end of a lever arm 50 pivoted within the casing 10. By means of a rod 51 secured to the lever arm 50 and projecting through the casing and provided with a handle, the clutch member 49 may be moved on the shaft 48 to either engage with or disengage 75 from the other half 41 of the clutch.

The clutch, being in engagement, it will be evident that the power will be applied through the frictional engagement of the member 42 and arms 44 to operate the mechanism of the horn. The tension of the spring 45 which draws the arms 44 together is so adjusted that at a certain predetermined and desired speed, the centrifugal force caused by the rotation of the member 43 on which the arms are mounted, will tend to force the arms outwardly against the action of the spring 45 to such an extent that they will release, or reduce the frictional engagement of the curved end 95 surfaces on the rotating member 42. In this manner, the rate of speed at which the actuating mechanism of the horn is driven may always be kept at or below a desired maximum. Thus, I have provided that the rate 100 of speed of the actuating mechanism shall never be so rapid as to become out of step with the desired periodicity or rapidity of the vibration of the diaphragm even when the rate of speed of the driving mechanism is 105 too high.

Having thus described my invention, what I claim as new and desire to secure by Letters Patent is:

1. In a signaling device, the combination 110 of a sound producing diaphragm, a rotary member for mechanically agitating said diaphragm, a prime mover, a shaft continuously revolved thereby, connections for driving said member from said shaft, said connections including a multiplying gearing connected to said member, a manually operable, positive clutch, and slip connections between said gearing and said clutch for limiting the speed of said gearing and said 115 rotary member by the vibratory speed of the diaphragm when the speed of said prime mover exceeds said vibratory speed.

2. In a signaling device, the combination 120 of a diaphragm, a shaft adapted to be secured and continuously driven by a prime mover, a friction disk, a positively acting controllable clutch for connecting said disk and said shaft, a rotary member for agitating said diaphragm, and connections between said 125 130

disk and said member and including a pair of opposed friction shoes engaging with said disk, and a spring for pressing them against said disk and resisting the tendency of centrifugal force to separate them from the latter.

3. In a signaling device, the combination of a diaphragm, a shaft adapted to be driven at varying speeds by a prime mover, a rotary member for agitating said diaphragm and connections between said rotary member and said shaft including a member operatively connected to said rotary member

and a spring for holding it in gripping relation to said shaft, said member acting 15 against said spring by centrifugal force and permitting increased speed and slipping of the said shaft when the speed of said rotary member exceeds a predetermined limit.

Signed at Sound Beach, in the county of 20
Fairfield and State of Connecticut, this 16th
day of July, A. D. 1915.

ALDEN W. McMURTRY.
